UNITED STATES PATENT OFFICE.

ELVEN ASH, OF BERKLEY, VIRGINIA.

SWITCH STRUCTURE.

1,027,792.

Specification of Letters Patent. Patented May 28, 1912.

Application filed July 26, 1911. Serial No. 640,608.

To all whom it may concern:

Be it known that I, ELVEN ASH, a citizen of the United States, residing at Berkley, in the county of Norfolk and State of Virginia, have invented certain new and useful 5 Improvements in Switch Structures, of which the following is a specification.

The object of the invention is to provide a special guard rail, and novel and peculiar 10 means for holding such rail to the railway rails at the frog sections of an ordinary track and to furnish special spacing blocks for bracing the guard rails relative to the track rails.

15 In the accompanying drawings forming a part of this application: Figure 1 is a plan view of the frog portion of a railway track. Fig. 2 is an enlarged cross section of a pair of rails showing a rail chair and 20 wheel in elevation. Fig. 3 is a perspective view of one of the rail chairs. Fig. 4 is an inverted perspective view of one of the blocks.

25 The same reference numerals denote the same parts throughout the several views of the drawings.

In the practical application of my invention the ordinary railway rails 1 and frogs 2 are employed. The guide rails 3 consist 30 of sections of ordinary railway rails having wheel-tread ends 4, which curve downwardly and inwardly from the rails 1. The rails 1 and the guide rails 3 are of the same, 35 depth and they are connected together and secured to the ties 5, by means of special rail chairs 6, and since all of such chairs are of the same construction only one of them 40 will be described in detail. Each chair comprises a pair of ears 7, which project 45 upwardly from the top face of the chair and are of such shape as to fit the rail web between the rail tread and the rail flanges of the rails 1 and 3. The top face of the 50 chair has two rail seats 8 and 9, and a slot 55 10 is formed between each of the ears 7 and the seats 8 and 9, respectively, for the outer flanges of the respective rails 1 and 3. The seat 8 is for the rails 1, and the seat 9 is dropped below the seat 8, by means of the 60 shoulder 11, which forms a lateral abutment for the outer flange of the rails 3, and said seat 9 holds the guard rails 3, below the 65 plane of the rails 1, for the purpose herein- 70 after more fully explained. A space or 75 brace block 12, is provided for each rail- 80 chair, and since all of said blocks are of

the same shape and construction only one 85 of them will be herein described. Said 90 block has a concaved top face to prevent its contact with the car wheel flange, and the 95 parallel sides of the block fit the inner sides of the webs of the rails 1 and 3 between the inner flange and tread of the rails 1 and 3; the bottom of the block is made angular 100 and is divided lengthwise by a shoulder 13, 105 and the face portion 14 is beveled from the 110 top of the shoulder to one side of the block and rests upon the flange of the rails 1, 115 opposite the rail chair face 8, and the face 120 portion 15 of the block is beveled from the 125 bottom of the shoulder to the other side of the 130 block and rests upon the inner flange of the 135 guide rails 3; opposite the rail chair face 140 9, so that the said faces 14 and 15 have 145 different angles and are of unequal depth from 150 the top of the block so as to accord with the 155 difference in elevation given the rails 1 and 160 3 by the rail chair seats 8 and 9. The 165 said block has a hole 16 therethrough for a tie 17, which extends through the ears 7 170 and the webs of the rails 1 and 3, and is 175 provided with a nut 18 and nut-securing 180 pin 19. The blocks 12 not only fill in the 185 space between the rails 1 and 3 at the rail 190 chairs, but such blocks form a substantial 195 and rigid brace between the rails and also 200 afford means for clamping the rails 1 and 3 205 between the rail chair ears 7 and the blocks 210 by operating the tie bolts 17. It will be 215 observed that the means (hereinbefore 220 described) for holding the rails is such as to 225 fix the guard rails 3 parallel with the rails 230 1, and to position the guide rails on a plane 235 below the plane of the rails 1.

I do not wish to be understood as confining 240 myself to any particular material and 245 size in the manufacture of my invention, nor to the application thereof to any particular 250 railway track, but reserve to myself the right 255 to make such changes in and various applica- 260 tions of my invention as may be found de- 265 sirable or as occasion may demand without 270 departing from the scope of the appended 275 claims.

Having thus described my invention what 280 I claim as new and desire to secure by Let- 285 ters Patent is:

1. The combination, with a railway track, 290 of a guard rail connected with each rail of 295 the track, of rail chairs having double rail 300 seats therein, one of which is elevated above 305 the plane of the other for holding the guard 310 rail, and since all of said blocks are of

rails below the plane of the track rails, ears projecting from the chairs with a slot between the ears and the seats for the inner flanges of the track rails and the guard rails, 5 and means for securing the chairs.

2. The combination, with a railway track, of a guard rail connected with each rail of the track, of rail chairs having double rail seats therein, one of which is dropped below 10 the plane of the other for holding the guard rails below the plane of the track rails, brace blocks fitting the adjacent sides of the track rails and the guard rails opposite said seats, and means for securing the blocks 15 and the chairs together and to all of said rails.
3. The combination, with railway track rails, and guard rails for the switch sections of the track, of means for connecting the

guard rails with the track rails so as to position the guard rails on a plane below the plane of the track rails, comprising rail chairs having a top face, a shoulder dividing the face into an upper and a lower rail seat, an ear extending inwardly from the 25 face at the outer end of each seat with a slot between the ears and the respective seats, brace blocks having an angular bottom fitting the inner flange of the track rails and the inner flange of the guard rails, and a 30 tie-bolt extending through the ears, the blocks and the webs of all of said rails.

In witness whereof I hereunto set my hand in the presence of two witnesses.

ELVEN ASH.
